UNITED STATES PATENT OFFICE

GEORGE M. LONG, OF FANEUIL, MASSACHUSETTS, ASSIGNOR TO WARREN TELECHRON COMPANY, A CORPORATION OF MAINE

DESIGN FOR A CLOCK CASE

Application filed October 3, 1930. Serial No. 37,126. Term of patent 14 years.

To all whom it may concern:

Be it known that I, GEORGE M. LONG, a citizen of the United States, residing at Faneuil, in the county of Suffolk, State of Massachusetts, have invented a new, original, and ornamental Design for a Clock Case, of which the following is a specification, reference being had to the accompanying drawings, forming a part thereof.

Fig. 1 is a front perspective view of a clock case showing my new design, and Fig. 2 is a side view thereof.

I claim:

The ornamental design for a clock case as shown.

In witness whereof I have hereunto set my hand this 27 day of September, 1930.

GEORGE M. LONG.
